SURFACE ORNAMENTATION OF WALLS.

No. 18,688.

Patented Oct. 16, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,688, dated October 16, 1888.

Application filed September 24, 1888. Serial No. 260,208. Term of patent 14 years.

To all whom it may concern:

Be it known that I, FREDERICK KOSKUL, of 5
Williamsport, Lycoming county, Pennsylvania,
have invented a new and original Design
for the Surface Ornamentation of Walls, &c., of
which the following is a specification, reference
being had to the accompanying photograph,
forming part hereof.

My design consists of—

- 10 First. A series of rectangular elevations, A,
having flat faces and inclined edges. Alternating
with said elevations are groups B, each
of three parallel raised bars. Said bars have
rounded faces and beveled extremities.
- 15 Second. A series of groups of nine small
rectangular elevations, C. Alternating with
said groups of elevations are groups of three
parallel bars, D. Said bars have rounded faces
and beveled extremities.

Third. A series of groups of nine small rect- 20
angular elevations, E. Alternating with said
groups of elevations are groups, F, of three par-
allel bars. Said bars have rounded faces and
beveled extremities.

The groups of bars D and F are similar and 25
appear parallel to and on two opposite sides
of the elevations A. The groups of elevations
C and E are also similar.

I claim—

The design for the surface ornamentation of 30
walls, &c., substantially as herein shown and
described.

FREDERICK KOSKUL.
